UNITED STATES PATENT OFFICE.

WILLIAM S. HAMM, OF LAKESIDE, ILLINOIS.

SIGNAL LAMP OR LANTERN GLASS HOLDER.

No. 874,402.

Specification of Letters Patent.

Patented Dec. 24, 1907.

Application filed July 14, 1905. Serial No. 269,660.

To all whom it may concern:

Be it known that I, WILLIAM S. HAMM, a citizen of the United States, and resident of Lakeside, in the county of Cook and State of Illinois, have invented certain new and useful Improvements in Signal Lamp or Lantern Glass Holders, of which the following is a specification, and which are illustrated in the accompanying drawings, forming a part thereof.

My invention relates to holders for colored glass plates, used in connection with signal-lamps of that type in which a frame, carrying a plate of colored glass, is movable into and out of register with the lens of the lamp.

The object of the invention is to provide means for removably securing a glass plate within the frame; and it consists, broadly, in the combination with a suitable frame for receiving the plate and a detent for engaging the latter at one of its edges, of a pivoted plate carried by the frame and adapted to swing over the glass plate and secure it to its seat.

It consists, further, in the provision of means for controlling the pivoted plate and of supplemental means for raising the glass plate from its seat as the securing plate is disengaged from it.

The invention is illustrated in the accompanying drawings, in which—

Figure 1 is a face view of the frame provided with a plate of glass and embodying one form of securing device; Fig. 2 is a sectional view on the line 2—2 of Fig. 1; Fig. 3 is a detail face view of the frame, showing a modified form of construction; Fig. 4 is a sectional detail on the line 4—4 of Fig. 3; Fig. 5 is a view similar to Fig. 3, showing a further modification; and Fig. 6 is a detail section on the line 6—6 of Fig. 5.

The frame or, as it is sometimes called in the art, the frame-arm for carrying the glass is substantially pear-shape, comprising an apertured body portion 10, within which the glass plate 11 is seated, and a stem 12 which serves as the means of attachment of the frame to the lantern with which it is to be used. The frame is preferably, though not necessarily, of sheet metal. As shown, its stem is reinforced by means of a plate 13, carrying an apertured hub or sleeve 14, the axis of which is perpendicular to the plane of the frame and which serves as means for pivotally attaching the frame to the lamp.

The body 10 of the frame has a marginal

upstanding or angular flange 15, which may be continuous, its function being to prevent lateral play of the glass plate 11. A lug or finger 16 projects inwardly from the upper edge of the flange 15, and may be integral therewith. This lug serves to hold the plate 11 to its seat at its outer edge. An oscillatable finger or plate 17 is pivoted at 18 to the frame at its base or stem side, and is of such length that its free end 19 will extend over the plate 11. When, as in the construction shown, the portion of the frame to which the plate 17 is pivotally secured is of less thickness than the glass 11, the plate is offset, as shown at 20, to bring its outer end to the proper plane.

In the form of construction shown in Figs. 3 and 4, the plate 17 is provided adjacent its outer end with an upstanding flange 21, which serves as a convenient means for applying pressure. In this form of construction the plate 17 is also provided with an arm 22, extending from its pivoted end at a slight angle from its body portion, the outer end of this arm being offset downwardly, as indicated at 23, to bring it to the surface of the body portion 10, the function of this arm being to pass under the glass plate 11 as the securing plate is moved out of engagement therewith, thereby raising the glass from its seat and facilitating its removal from the frame.

In order to lock the securing plate 17 against accidental displacement, a boss 17^a may be formed in its under surface for frictionally engaging a complementary recess 13^a formed in the upper face of the plate 13.

In the modification illustrated in Figs. 5 and 6, a securing plate 24 is shown which is more nearly circular in form and slotted radially, as shown at 25, and so bent that one of the lips, as 26, formed by the slot will ride over and the other, 27, will pass under the plate 11. In this preferred construction the inclination of the two plates is such that they act upon the glass as cams, the one for forcing it to its seat and the other for forcing it therefrom. The body 10 is depressed, as shown at 28, to form a recess for receiving the lower lip 27 of the plate 24, and a boss 29 is struck up from the bottom of this recess for frictionally engaging this lip and thus locking the plate 24 against accidental movement. In this form of construction the plate 24 is provided with a laterally projecting arm 30, which extends beyond the body

10 of the frame, and is provided with a finger-piece 31, thereby more conveniently facilitating the operation of securing or removing the glass. The outer end of the arm 30 is 5 also provided with a downwardly - turned flange 32, which serves as a stop by engaging the edge of the body 10.

The stem 12 of the frame and the plate 13 may be secured together in any desired manner. As illustrated in Fig. 3, such securing 10 means consists of rivets 33. In the construction of Fig. 5, the two parts are secured together by means of lugs 34, 35, formed on the member 12 and folded over the plate 13.

15 I claim as my invention.—

1. In a signal-lamp or lantern, an apertured frame-arm for a color-glass having an angular rim extending around the major portion of the periphery of the glass, a finger 20 overturned from the rim at one side and a pivoted plate at the opposite side with an offset free end to pass over the edge of the glass.

2. In a signal-lamp or lantern, an apertured frame-arm for a color-glass having an angular rim extending around the major portion of the periphery of the glass, a finger 25 overturned from the rim at one side, a pivoted plate at the opposite side with an offset free end to pass over the edge of the glass, and means for holding the said pivoted plate 30 in place free from accidental displacement by vibration.

3. In a signal-lamp or lantern, an apertured frame-arm for a color-glass having an angular rim extending around the major portion of the periphery of the glass, a finger 35 overturned from the rim at one side, a pivoted plate at the opposite side with an offset 40 free end to pass over the edge of the glass, the frame-arm being provided with a recess and the pivoted plate with an interlocking projection for holding said pivoted plate in an initial position of use free from accidental 45 displacement by vibration.

4. In a signal-lamp or lantern, an apertured frame-arm, composed of an apertured sheet - metal part and a plate connected thereto by rivets, a rim formed on the sheet-metal part bounding the major portion of the aperture therein and into which rim the color-glass is adapted to be received and fit, a finger overturned from the rim at one side and a pivoted plate with an offset free end to 55 extend over the opposite edge of the color-glass, secured to the plate portion of the frame-arm and adapted to be turned toward the glass to hold the same, or away from the glass to release the same.

5. In a device of the kind described, in 60 combination, a frame having a seat for a plate of glass; and a two-arm plate pivoted to the frame, the free ends of the plate arms extending over the seat and being spaced apart axially so that they will engage opposite 65 site faces of a plate of glass on the seat.

6. In a device of the kind described, in combination, a frame having a seat for a plate of glass; and a plate pivoted to the frame and extending across the seat, such 70 plate being radially slotted, the lips of the slot being oppositely inclined axially.

7. In a device of the kind described, in combination, a frame having a seat for a plate of glass; and a plate pivoted to the 75 frame and extending over the seat and being provided with a controlling arm projecting beyond the edge of the frame.

8. In a device of the kind described, in combination, a frame having a seat for a 80 glass plate; a plate pivoted to the frame and being radially slotted, the lips of the slot being oppositely inclined axially, such plate having a controlling arm projecting beyond the edge of the frame. 85

9. In a device of the kind described, in combination, a frame having a seat for a plate of glass; and a plate pivoted to the frame and extending across the seat, such plate being radially slotted, the lips of the 90 slot being oppositely inclined axially, the seat in the frame being depressed to receive one of the lips of the plate.

10. In a device of the kind described, in combination, an apertured arm having a seat 95 for a glass plate; and a securing plate attached to the frame and movable to engage the glass when occupying the seat.

11. In a device of the kind described, in combination, an apertured arm having a seat 100 for a glass plate; a securing plate attached to the arm and movable to engage the glass when occupying the seat; and a reciprocating plate carried by the arm and arranged to pass under the glass when occupying the 105 seat.

12. In a device of the kind described, in combination, a frame having a seat for a plate of glass; and a two-arm plate pivoted to the frame, the free ends of the plate-arms 110 extending over the seat and being spaced apart axially and radially so that they will engage opposite faces of a plate of glass on the seat.

WILLIAM S. HAMM.
